UNITED STATES PATENT OFFICE.

FREDERICK HACHMANN, OF ST. LOUIS, MISSOURI, ASSIGNOR TO WILLIAM H. GREGG,
OF ST. LOUIS, MISSOURI.

MILK-BOTTLE CLOSURE.

1,418,439.

Specification of Letters Patent. Patented June 6, 1922.

Application filed February 14, 1921. Serial No. 444,912.

To all whom it may concern:

Be it known that I, FREDERICK HACHMANN, a citizen of the United States, and resident of the city of St. Louis, State of Missouri, 5 have invented certain new and useful Improvements in Milk-Bottle Closures, of which the following is a specification containing a full, clear, and exact description, reference being had to the accompanying 10 drawings, forming a part hereof.

My invention relates to improvements in milk bottle closures, and has for its primary object the construction of a cover particularly designed for use on milk bottles 15 after the ordinary paper disc or cover has been removed therefrom, but it is obvious the same is also useful as a closure for other bottles in place of ordinary corks or other closures.

20 A further object of my improvement is to construct a cheap and efficient closure which may be applied and detached to various forms and constructions of bottle necks.

25 In the drawings:

Fig. 1 is a sectional view of a closure and portion of a bottle neck of the milk bottle type.

Fig. 2 is a top plan view of the closure 30 stamped from a single piece of metal and before the same is formed.

Fig. 3 is a side view of the clamp by means of which the closure may be fastened to a bottle neck.

35 Fig. 4 is an end view of the same.

Fig. 5 is a plan view of the spring by means of which the lid of the closure is clamped to the bottle.

Referring to the drawings, 6 indicates the 40 closure lid and 7 the handle. These parts being formed integral and stamped from a single piece of material, as illustrated in Fig. 2. Formed integral with the handle portion 7 are perforated ears 8. The lid

45 portion 6 is slightly concaved, as at 9, to conform and fit the top edge of the bottle neck. After the lid portion 6, the handle 7 and the perforated ears 8 have been stamped they are conformed and bent for use, as 50 illustrated in Fig. 1. 9^a indicates the means by which the closure is fastened to the bottle neck. This clamp has two spring arms 10 and 11, which depend from the central

portion 12. The arm 10 is provided with an inwardly curved or bent portion 13 and 55 with an offset portion 14. This offset portion, when the device is in use, rests in the seat 15 primarily used for the ordinary paper disc or cover. The arm 11 of the fastener is provided with an outwardly curved 60 portion 16 and with an inwardly curved portion 17, which when the device is in use binds or rests against the external flange 18 of the bottle neck. The arm 11 near its terminal portion is further provided with an inwardly projecting tooth or prong 19, which 65 also engages the flange 18 of the bottle. Formed integral with the fastening device 9^a and especially with the arm 11 of said device are trunnions 20. These trunnions 70 are adapted to fit in the perforations 21^a of the ears 8. Mounted on these trunnions is a coil spring 21, the central portion 22 of which is located beneath the portion 12 of the fastener and the free ends 23 rest beneath the handle 7. By means of this 75 spring the lid of the closure is held seated on the top edge of the bottle neck.

After my device has been constructed as described, it is applied to the bottle by 80 means of seating the same on the neck thereof, the arm 10 being seated on the inside surface of the bottle neck and the arm 11 on the outside surface thereof and the portion 12 resting on the top edge thereof. 85 The arms 10 and 11 being inherently elastic will exert a clamping action on both the inside and outside surfaces of the neck and against the flange formed thereon, the prong 19 assisting in holding the closure in place. 90

By reference to Fig. 1 it will be observed that the pressure necessary to open the lid will be exerted against the lower portion of the flange 18 and, therefore, not lift or displace the closure from the bottle 95 neck.

Having fully described my invention, what I claim is:

A bottle closure comprising a lid and handle portion stamped from a single piece of 100 metal, perforated ears formed integral with the handle portion, a clamping member pivotally connected to the handle portion, said clamping member being provided with two depending spring arms of uniform and equal 105 widths and having their lower ends curved

in opposite directions, the outer one of which is provided with an inwardly and upwardly projecting tooth and the inner one with an offset portion, which are adapted to clamp the bottle neck at opposite points on the inside and outside surfaces thereof and the said tooth adapted to engage the bottle neck

to prevent the closure from being accidentally displaced, and a spring mounted on said clamping member for holding the lid 10 member closed.

In testimony whereof, I have signed my name to this specification.

FREDERICK HACHMANN.
